GAME TRAP

Filed April 3, 1926

INVENTOR
LESTER A. BEARDSLEY
BY *Charles A. Wilson*
ATTORNEY

UNITED STATES PATENT OFFICE.

LESTER A. BEARDSLEY, OF NORWICH, NEW YORK, ASSIGNOR TO NORWICH WIRE WORKS, INC., OF NORWICH, NEW YORK, A CORPORATION OF NEW YORK.

GAME TRAP.

Application filed April 3, 1926. Serial No. 99,506.

This invention relates to game traps, more particularly to that type of trap wherein a pair of opposed gripping jaws pivotally mounted upon a base member or foundation, 5 are operated by spring actuating means operating upon both of said jaws.

One of the objects of the invention is to provide a new and improved trap of exceedingly simple construction, which is nevertheless 10 less most efficient in operation.

Another object of the invention is to provide a trap of the coil spring type, wherein the number of operative parts is reduced to a minimum, thus reducing the cost of production, both as to amount of material employed in the trap and in the ease of 15 assembly.

Other objects and aims of the invention, more or less specific than those referred to 20 above, will be in part obvious and in part pointed out in the course of the following description of the elements, combinations, arrangements of parts and application of principles, constituting the invention; and 25 the scope of protection contemplated will be indicated in the appended claims.

In the accompanying drawing, wherein I have illustrated a preferred form of embodiment of my invention,

30 Figure 1 is a top plan view of my improved trap, showing the same in unset condition.

Figure 2 is a side elevational view of a portion of the trap, showing the same in the 35 unset condition of Figure 1.

Figure 3 is a top plan view of my improved trap, showing the same in set condition, and

40 Figure 4 is a vertical sectional view of the trap in set condition, taken on the line 4—4 of Figure 3 looking in the direction of the arrows.

Referring now to the drawings, wherein 45 similar reference characters refer to similar parts throughout the several views of the drawing, the reference numeral 1 denotes the base or foundation of the trap, 2 the cross piece which is anchored to the foundation 1 intermediate its ends as by means of the 50 rivet 3, said cross piece 2 having its edges preferably flanged upwardly to give it strength and stiffness. The cross piece 2 extends laterally of the trap and is provided at its outer end with an upwardly extending

flange 4 upon which is pivotally mounted 55 a detent 5. Pivotally mounted upon the pin 6 which extends through the flanges 7 and 8 of the cross piece, is an arm 9, upon which is mounted the pan 10 of the trap. The arm 9 is recessed as at 11 to form the 60 shoulder 12 under which the detent 5 is received when the trap is set, as clearly illustrated in Figures 3 and 4.

The reference numerals 13 and 14 denote 65 the jaws of the trap, which jaws have formed upon their end portions the pintles 15 and 16 respectively, said pintles being received in apertures formed in upwardly extending flanges 17 and 18 provided respectively upon the outer ends of the foundation 1.

As thus far described, this trap does not 70 differ materially from other well known forms of game traps.

Referring now to the actuating means for 75 the jaws of the trap, the reference numeral 19 denotes the spring actuating member for closing the jaws. This actuating member is preferably comprised by a length of relatively stiff spring wire, bent upon itself to 80 form the loop 20, portions of the legs 21 and 22 of said loop intermediate their ends being formed into the coils 23 and 24. The ends 25 and 26 of the legs of the loop upon leaving the coiled formations 23 and 24 extend 85 rearwardly and have upstanding free ends 27 and 28 which extend upwardly through the apertures 29 and 30 formed in the cross piece 2. One of these apertures 29 is formed 90 in the end of the cross piece and the other aperture 30 is formed intermediate the ends of the cross piece; the apertures being preferably located equidistant from the side edges 31 and 32 of the foundation or base member 1.

The reference numeral 33 denotes a cross 95 bar which extends transversely of the foundation 1 and rests thereon, said cross bar having a downwardly struck lug or projection 34 which extends downwardly through an aperture 35 formed in the base or foundation 1, whereby said cross bar in the position shown in the drawing, is anchored against relative length-wise or transverse movement with respect to the foundation when the parts are in the operative positions shown in the drawing. The cross bar 33 has its ends 36 and 37 extending laterally of the founda- 100 105

tion, and upon these extending ends 36 and 37 are mounted the coils 23 and 24, of the actuating member.

The inner ends of the coils 23 and 24, it will be noted, have lateral engagement with the sides 31 and 32 of the foundation 1, and are spaced apart by the said foundation member. The anchoring of the rearward extensions 25 and 26 in the cross piece 2 prevents a relative upward movement of the coils 23 and 24 of the actuating member. Thus, it will be seen that the coils 23 and 24 which are firmly supported upon the cross bar 33, are also locked against relative lateral movement in either direction.

The jaws 13 and 14 at the end of the trap adjacent the actuating member are provided with the inclined shoulders 38 and 39, which shoulders are traversed by the legs 21 and 22 of the loop 20 when the trap is sprung, and the loop moved upwardly by the coils 23 and 24 of the spring, the upward movement of said loop being arrested in the position shown in Figures 1 and 2 when the jaws have been moved into engagement, in which position the jaws are locked together by the legs 21 and 22 of the actuating member.

In the present instance, the leg 21 of the actuating member is provided with a depression 40 and the leg 22 with a raised portion 41, the object of which construction being to permit the jaws to lie in a substantially parallel plane and in a plane substantially parallel to the plane of the pan 10 when the trap is set. It will be noted that when the trap is set against the tension of the actuating member, the locked jaw 14 being held against upward movement by the detent 5, there is a tendency to give the loop 20 a slight lateral twist, which ordinarily would elevate the leg 21 of the spring to such a position that it in turn would elevate the free jaw 13, whereby this jaw would not lie in a plane parallel with that of the locked jaw 14. The provision of the depression 40 and the raised portion 41 on the legs 21 and 22 respectively, compensates for this slight twist given the loop 20 when the trap is set.

It will be noted that when parts of the trap are in assembled relation, whether the latter is in set or unset condition, the actuating member is at all times under stress, whereby the cross bar 33 is always pressed downwardly against the foundation 1, in which position, as already described, it is held against lateral or longitudinal movement relative to the foundation 1, by the locking engagement of the lug 34 with the walls of the aperture 35. It is, therefore, not

necessary to rivet or otherwise permanently secure the cross piece 33 to the foundation 1.

It will accordingly be seen that I have provided a game trap composed of relatively few parts, whereby there is formed a trap of exceedingly compact formation. Being composed of relatively few parts, the trap may be produced very cheaply. It is also assembled very easily.

As many changes could be made in this construction without departing from the scope of the following claims, it is intended that all matter contained in the above description or shown in the accompanying drawing shall be interpreted as illustrative only, and not in a limiting sense.

Having thus described my invention, what I claim as new and desire to secure by Letters Patent, is:

1. The combination in a game trap, of a foundation, a pair of cooperating jaws pivotally mounted upon the foundation, a bait pan, escapement devices engaging the pan and arranged to hold the jaws open when the trap is set, and an operating open spring having portions bearing against, and adapted to throw the said jaws together when the trap is sprung, one of the said portions of the spring having a raised part bearing against one of the said jaws, and the other portion of the spring having a depressed part bearing against the other jaw whereby the said jaws will rest when open substantially in the same horizontal plane, the said raised and depressed portions of the spring being arranged opposite each other.

2. The combination in a game trap, of a foundation, a pair of cooperating jaws pivotally mounted upon the foundation, a bait pan, escapement devices engaging the pan and arranged to hold the jaws open when the trap is set, and an operating loop spring having portions bearing against and adapted to throw the said jaws together when the trap is sprung, the said spring comprising a single piece of resilient wire having a loop, one side of the said loop having a raised part bearing against one of the said jaws, and the other side of the loop having a depressed part bearing against the other jaw whereby the said jaws will rest when open substantially in the same horizontal plane, the said raised and depressed portions of the wire being arranged opposite each other.

In testimony whereof, I affix my signature.

LESTER A. BEARDSLEY.
